A. McMURRAY

ELECTRIC TRUNCHEON TORCH

Filed April 25, 1925

Inventor:

Alexander McMurray

UNITED STATES PATENT OFFICE.

ALEXANDER McMURRAY, OF AUBURN, SYDNEY, NEW SOUTH WALES, AUSTRALIA.

ELECTRIC TRUNCHEON TORCH.

Application filed April 25, 1925, Serial No. 25,878, and in Australia November 5, 1924.

My invention relates to improvements in an electric truncheon torch the object of which is to provide police and those engaged in a like lawful capacity by night with an instrument of search and a reliable means of defence in which the construction has been so arranged that on it being used for the latter purpose the only damage likely to befall the instrument would be the breaking of the filament of the electric light bulb and to meet this contingency extreme accessibility and the most rapid method of disassembling and re-assembling has been employed. For instance in Figs. 1 and 2 three movements of the mechanism suffice to expose all the interior working parts whilst in Fig. 10 a similar object is achieved by two operations. A further object of converting the invention for use as an ordinary police truncheon is attained by withdrawing the inner parts required for lighting purposes and replacing them by a dummy of some suitable material.

I attain these objects by the mechanism illustrated in the accompanying drawings.

Fig. 1 is an elevational view of the invention.

Fig. 2 is a longitudinal section of Fig. 1.

Fig. 3 is a cross section on line 3-3 of Fig. 1.

Fig. 4 is a perspective view of the electric conductor battery cage with spring contact and reflector.

Fig. 5 is an alternative spring contact and buffer.

Fig. 6 is a part longitudinal sectional view of an alternate method of attaching the handle to the tubular casing by screwing, with battery, lamp and spring contact removed for clearness.

Fig. 7 is a part sectional view of a further alternative method of attaching the handle to the tubular casing by screwing.

Fig. 8 is a broken view of an alternative method of attaching the handle to the tubular casing by a bayonet socket.

Fig. 9 is a part broken sectional view of a further alternative method of attaching the handle to the tubular casing by a bayonet socket.

Fig. 10 is a part sectional view of an alternative method of attaching the handle to the tubular casing by means of press springs and pins.

Fig. 11 is an alternative method of forming a switch press button for lighting the torch.

Fig. 12 is an alternative method of forming a switch press button for lighting the torch when applied to a hollow metal handle.

Figs. 13^a, and 14^b, are different sectional views of alternative methods of attaching handle to tubular casing by screwed and flanged unions.

Fig. 15^c is a sectional perspective view of attaching handle to tubular casing by 65 screwed and flanged unions and pins abutting flange.

Fig. 16^d is a modification of Fig. 2 of that portion where the handle is attached to the tubular casing.

Fig. 17^e shows tubular casing uncovered and a dummy filling in the interior thereof.

Similar numerals, and numerals with letters, refer to similar parts throughout the several views.

13 is the handle of wood or other material having a safety strap 14 for the wrist of the user; a metal tubular casing 15 having an outer buffer casing of rubber 16 or other resilient material. In the interior of the tubular casing 15 is an electric torch battery 17 the latter being enclosed by an electric battery conductor cage 18 having attached at one end a lamp screw socket 19 and lamp reflector 20. In the lamp socket 19 is an electric lamp 21 situated behind the projector lens 22 formed on one end of the tubular casing 15. An alternative projector lens may be attached by means of a screwed socket 22^a screwed into the outer end of the tubular 90 casing 15 as shown in Fig. 6. Attached to the opposite end of the electric battery conductor cage 18 is a buffer contact spring 24 having a contact plate 25. A switch press button 26 with angularly disposed press pin 27 attached thereto is adapted to impinge against the contact plate 25 attached to the buffer contact spring 24 to compress the latter thereby making electric contact with one pole or carbon 28 of the battery 17 the circuit being thus completed to light the lamp 21, the current passing by way of contact plate 25, buffer spring 24, battery conductor cage 18, reflector 20, lamp screw socket 19, lamp 21 thence returning through insulated contact 29 to the other pole or zinc of battery 17. In Fig. 5 is shown an alternative method of applying the buffer contact spring 24 the latter being attached to a secondary spiral buffer spring 30 by means of a socket joint 31. The handle 13 is removably attached to the tubular casing 15 by means of

the split ring 32 the latter having firmly attached thereto the pins (one or more) 33, the said pins 33 passing through oppositely bored holes in the tubular casing 15 and 5 metal ferrule 34 attached to shoulder of handle 13.

In Fig. 6 is shown an alternative method of attaching the handle 13 to the tubular casing 15 where the metal ferrule 34 is internally threaded to fit external threads cut on the tubular casing 15. Fig. 7 is a further alternative of Fig. 6 of attaching the handle 13 to the tubular casing 15 where the metal ferrule 34 on the handle 13 is externally threaded to fit the internal threads cut on inside of the tubular casing 15. In Figs. 8 and 9 bayonet sockets are alternatively adapted to removably attach the handle 13 to tubular casing 15, where in Fig. 8 the metal ferrule 34 of the handle 13 is fitted to slide internally into tubular casing 15 and is provided with pins 35 to fit and engage the slots 36 and is also adapted to fit and slide externally over the tubular casing 15 and engage the pins 35 provided in the latter. A further alternative of removably attaching the handle 13 to tubular casing 15 is shown in Fig. 10 where set pins 37 attach firmly to press springs 38 which latter are secured by screws at one end to the handle 13, the pins 37 passing outwardly through the metal ferrule 34 and tubular casing 15 which lock the handle 13 and tubular casing 15 firmly in position. By depressing the press springs 38 into the slots 39 in the handle 13 the set pins 37 are disengaged from the holes in the ferrule 34 and tubular casing 15 when the handle 13 may be readily withdrawn. An alternative method of applying an electric press button to the handle 13 is shown in Fig. 11 where the press pin 27 provided with a press button 26 arranged to slide in a hole bored centrally and horizontally through the handle 13. In Fig. 12 is an alternative method of using a hollow metal handle 40 having a press button 26 and an angularly disposed press pin 27, the latter having a hinged joint 41 attached to a sliding pin 42 sliding in a guide tube 43 attached to the end cap 44 allowing free play of the angularly disposed pin when the latter is depressed by the press button 26. A further alternative method of attaching the handle 13 to the tubular casing 15 as shown in Fig. 13^A, is effected by a threaded union 45 with flange 46 held on tubular casing 15 by circumferentially arranged stud pins 47, or shoulder, on tubular casing 15 fitted to screw on to corresponding thread on outside of ferrule 34 of handle 13. Fig. 14^B, shows a reversal of the action in Fig. 13^A, inasmuch as threaded union 45 with flange 46 is held on ferrule 34 of handle 13 by circumferentially arranged stud pins 47, or shoulder, on

ferrule 34, fitted to screw on to corresponding 65
thread on outside of tubular casing 15. Fig. 15^C, shows a sectional perspective view
of attaching the handle 13 to tubular casing
15 by screwed flange and union with pins
abutting flange as illustrated in Figs. 13^A, 70
and 14^B. Fig. 16^D, is a modification of Fig.
2 inasmuch as the action therein is reversed
by ferrule 34 of handle 13 being constructed
to fit over tubular casing 15 instead of in
the interior thereof. As a further alterna- 75
tive the handle 13 may be made a fixture in
tubular casing 15 by constructing handle 13
and tubular casing 15, in one piece, or affix-
ing the handle 13 in the tubular casing 15 by
screws and the interior of the latter ren- 80
dered accessible by removing screw cap of
flange 22^A Fig. 6, and the tubular casing left
uncovered, and filled with a dummy filling
of some suitable material 48 as shown in
Fig. 17^E, or covered as already described. 85

I prefer to carry out the features of my invention as embodied in Figs. 1, 2, 3, 4, 5, 10, 12, 16^D, and 17^E.

I am aware that prior to my invention improvements have been made in electric torches, I, therefore, do not claim such improvements broadly, but I claim:—

1. A truncheon torch comprising a weighted hollow body, a detachable handle for said body, a removable electric battery and reflecting lamp within said body, a light projector lens associated with said body and lamp, electric conductive means including a metal carrier for the battery extending from the opposite poles of the battery, compressible means fitted at one end of the carrier and having a contact button for one pole of the battery, the opposite end of the carrier being fitted with the electric reflecting lamp, and a contact on the lamp adapted to make contact with the opposite pole of the battery, and means associated with said handle whereby the circuit of said battery is closable through operating said contact button to electrically connect the poles of said battery through said conductive means.

2. A truncheon torch comprising a hollow body having one end weighted, a detachable handle for the opposite end of said body, a removable electric battery and reflecting lamp within said body, a light projector lens associated with said body and lamp, electric conducting means associated with said battery and poles thereof, one end of the handle being provided with a hole, a metal push rod fitted in the hole, a push button on the outer end of the rod and disposed to be operable externally of the handle, and a contact button associated with the electric means of the battery and contacted by the inner end of the rod.

ALEXANDER McMURRAY.
